Company of California, San Francisco, Calif.,
a corporation of Delaware

Application December 17, 1929, Serial No. 414,817

16 Claims. (Cl. 48—195)

This invention relates to a volatile compound for use as an odorant for natural gas and other heating or illuminating gas, including the vaporized and gaseous product resulting from liquid or liquefied petroleum fractions. More particularly, the invention relates to a heating or illuminating gas containing a novel odorant produced from what has heretofore been considered a waste product; namely, acid sludge, which results 5 from the treatment of petroleum oils with sulfuric acid.

Ordinarily natural gas and other fuel gases do not, of themselves, possess sufficient odor to warn of their presence when they escape from the containers, piping, or fixtures wherein they are used; and a danger results in such instances due to the explosive or toxic hazards created.

Natural gas, such for example as is obtained from natural gas wells and oil wells, does not 20 possess a marked color. Consequently, when natural gas is used for heating, cooking or illumination in the home or in industrial plants, it is possible for asphyxiative or explosive quantities of the gas to accumulate unnoticed by the persons in contact with the gas.

Various odorants have been used heretofore to give the gas a characteristic odor which will give proper warning of danger. So far as is known, all odorants heretofore employed have one or 30 more objections. Some odorants are not distinctive and do not rouse the victim to action, or the odorant, while distinctive, may be so offensive that users of the gas containing the odorant object to the odor. With some odorants excessive 35 quantities of odorant are required.

The heating and illuminating gas which is the subject of the present invention contains an odorant which has a distinct and penetrative odor. It is easily and unmistakably detectable before 40 explosive mixtures or asphyxiative concentrations are reached. In addition merely of warning one of its presence it is sufficiently distinctive to rouse one to action. On the other hand it is not so obnoxious as to be objectionable to the customer.

When used in proper proportions the odorant embraced by this invention does not produce any undesirable physiological action such as skin irritation, lachrymation, or the like. Furthermore, the products of combustion are substantially 45 odorless when used in the proportions necessary to impart distinct warning characteristics to the gas. An object of this invention, therefore, is to disclose and provide a gaseous hydrocarbon fuel 50 containing a novel odorant which is readily detectable by the olfactory organs but which does

not impart undesirable properties to the fuel. Another object is to disclose and provide a method of producing a hydrocarbon gas which is capable of signalling its presence through the olfactory organs, even when present in low concentrations, said gas being substantially odorless when burned. 5

In this novel odorant there exists a series of volatile organic compounds. While most of these are believed to be principally organic sulfides of the saturated ring heterocyclic type, containing three or more carbon atoms and sulfur as a hetero-atom, other organic sulfur compounds such as aliphatic sulfides, disulfides, polysulfides, mercaptans and thiophene homologues may be 15 incidentally present. There may also be present non-sulfur bodies. The saturated ring heterocyclic sulfides referred to are to be distinguished from hydrosulfides or mercaptans (R—S—H type), and from thiophenes which contain only 20 four carbon atoms and are unsaturated. They have an odor which is distinct from the odor of common mercaptans and from thiophenes, and principally comprise the effective odorizing constituents of the odorant oil herein described. 25 Their odor is readily distinguished from the mild odor of the thiophenes, it being remembered that disulfides have practically no odor and are of no importance in the performance of this invention. Some of these sulfur compounds are of the type 30 such that they have a distinctive, intense and penetrative odor so that minute quantities can be used to impart the necessary odor to the gas. The quantities required are so small that the sulfur content of the gas is not appreciably increased over that which ordinarily exists in the 35 gas.

The odorant embraced by this invention is distinctly perceptible by most people when it exists at a concentration of 0.25 part per million. 40 In other words when the product is used in the proportion of three gallons per million cubic feet of gas, it will produce a distinct odor when a sufficient quantity of the gas is admitted into the room so that 0.5 per cent of the odorized gas is 45 present in the air thereof. These sulfur compounds occur in many petroleum oils so that when such oils are treated with suitable reagents, such as sulfuric acid, they will be found to exist in the resulting acid sludge. This sludge may be distilled or it may first be subjected to hydrolysis 50 and then distilled to produce a volatile component in which these sulfur compounds will be found.

The sulfuric acid may react on certain of the compounds normally existing in oil so as to 55

change them in molecular structure during the recovery process.

The properties of the odorant may vary considerably and may depend upon the type of sludge from which it is obtained and the volatile portion of the sludge oil selected as the odorant. The variation in the physical and chemical properties of the odorant is shown by the following inspections on five different odorants, any one of which 10 or any combination of which will produce a suitable odorant.

15	Type of sludge	Cracked gasoline	Straight run gasoline	Kerosene	Mixture of cracked gasoline, kerosene, liquid petroleum	Mixture of cracked gasoline, kerosene, liquid petroleum
20	Odorant:					
	Gravity, °A. P. I.	30.8°	26.6°	27.0°	25.7°	43.0°
	Percent sulfur	9.18%	15.48%	2.13%	4.68%	5.09%
	Color Saybolt	Below	Below	Below	Below	Below
25	Flash, closed tag	Below	80° F. +	100° F. +	124° F.	Below 80° F.
	A. S. T. M. Dist. range:					
	Start	160° F.	252° F.	300° F.	310° F.	112° F.
	Percent distilled	20%	284	312	352	372
		50%	349	335	372	406
30	End point	90%	490	386	430	466
			495	432	453	524
						390

The color of the odorant ranges from water white to yellow or amber, but is usually yellow.

35 While the properties of the odorants listed above vary considerably it is possible to control the process of production so as to obtain a uniform odorant having any desired properties. We find that the sulfur content of our odorant may 40 range from 2% to 30%, by weight, of the odorant, but usually does not exceed 18%.

The boiling point range of the odorant may range between 100° F. and 600° F. The selection of a suitable boiling point range for any specific 45 odorant will depend upon two factors; first, the amount of odorant required to impart a noticeable odor to the gas; and second, the temperature and pressure under which the gas is stored and distributed. It is essential that odorant should 50 evaporate completely and the distillation of the sludge should be carried out with this in mind. Since gas is distributed under varying pressures and temperatures an odorant must be selected which will evaporate under the highest pressure 55 and lowest temperature existing in the distributing system. We find, for example that where gas is distributed at pressures as high as 250 pounds per square inch and at temperatures as low as 55° F. the odorant should have an end 60 point not over 420° F. and should yield 70% by distillation at 340° F. With lower pressures and higher temperatures, odorants having higher boiling points can be used. Likewise, for higher pressures and lower temperatures the odorant 65 should have lower boiling points.

The concentration of odorant required in the gas to produce the distinct and penetrating odor desired is an important factor in the selection of an odorant. An odorant made from sludge resulting from the acid treatment of raw cracked gasoline or straight run gasoline is particularly desirable on account of the low concentrations required to produce a satisfactory odor.

It should be noted, however, that the method 70 of treating may also influence the character of

the odorant. Thus two sludges produced from the same oil stock but with different acid treatments such as with various kinds, amounts or strengths of acid at different temperatures will have different physical properties. The lighter 5 petroleum oils such as naphthas, gasoline, and kerosene are the best source of volatile organic sulfur compounds although small amounts of volatile organic sulfur compounds can be obtained from higher boiling point petroleum oils. 10

The foregoing description has defined the physical and chemical characteristics of the odorant insofar as this can be done and has set forth briefly the source from which the odorant is obtained. The following descriptions relate to different methods of obtaining the odorant from the sludge and are given to enable those skilled in the art to produce the odorant. 15

Petroleum oils are usually treated with acids for removal of impurities. Among the impurities 20 which it is desirable to remove are the organic sulfur compounds. These are commonly removed by the use of such acids as sulfuric acid, including fuming sulfuric acid, sulfuric anhydride (SO₃), or sulfur dioxide. The organic sulfur 25 compounds are composed mainly of organic sulfides, disulfides, polysulfides, mercaptans and thiophene homologues.

During the acid treatment these organic sulfur compounds are dissolved in or combined with 30 the acid. In either event they will be found in the sludge resulting from the acid treatment.

The odorant which is the subject of this invention can be obtained, containing these organic sulfides, by distilling the sludge by any of 35 the well-known methods, either at atmospheric or superatmospheric pressure or with vacuum, and condensing the volatilized constituents resulting from the distillation. The condensate formed is an oily compound. A part of the acid 40 component of the sludge is distilled over with the sulfur compounds and a part is reduced to sulfur dioxide, both of which are recovered from the condenser. Some of the SO₂ will be dissolved in the water formed during the distillation while 45 most of the SO₂ will pass off as a gas. The acid distillate readily separates from the oily compound in the condenser. The oily compound is withdrawn separately and may be further purified, if necessary, by neutralizing and washing 50 with water. The neutralization may be desirable so as to remove any sulfur dioxide or acid which may be present, thereby preventing any corrosion in the gas lines or containers. The resulting finished product which is the odorant is passed 55 to storage. If desired, the volatile oil vapors may be condensed by means of a fractional condenser.

Although the desired odorant can be obtained by simple distillation of some sludges, it is preferred, with most sludges, such as the sulfuric 60 acid sludges, to first hydrolyze the sludge to produce a weak acid and a tar, the odorant being recovered from the tar by distillation. The usual method of recovery is to add water to the sludge causing it to hydrolyze into weak sulfuric acid 65 and an organic remainder sometimes called a tar. Some sludges are readily hydrolyzed at normal temperatures, whereas others require heating. Some sludges require heating at temperatures above their boiling point, thus necessitating the 70 use of pressure above atmospheric in order to reach the high hydrolyzing temperature. The acid and tar separate into two layers and may be recovered separately. The upper or tar layer contains the odorant.

If the tar from which the odorant is to be obtained has been produced by hydrolyzation of sludge at normal temperatures, that is, without the application of heat to the hydrolyzing chamber, it is necessary to distill the tar and recover those fractions which are distilled off at temperatures up to about 600° F. and which are condensable at atmospheric pressures. Any of the conventional distilling apparatus may be employed. A fractional condenser may be used to collect and separate any desired portion of the vapors.

If the tar from which the odorant is to be obtained has been produced by steaming or heating in an open tank, a more volatile odorant will be produced. If it is desired to lower the volatility of the odorant this can be accomplished by distilling and fractionally condensing such portions of the vapors as are desired for the odorant.

If the tar from which the odorant is to be obtained has been produced by hydrolysis at high temperatures and super-atmospheric pressures, the volatile fractions of the tar can be obtained by passing the tar from the sludge digester, through a pressure regulating valve, into an evaporating chamber. The volatile portions of the tar containing the odorant may be vaporized by the residual heat in the tar and may be withdrawn from the chamber and condensed. Inasmuch as the volatile tar vapors from the evaporator are usually accompanied by some sulfur dioxide vapors it is desirable to separate them from each other. Since sulfur dioxide gas is readily soluble in water a separation can be obtained by passing all of the vapors from the vaporizing chamber through a body of water or through a scrubbing tower. One convenient method of separating the vapors is to remove them from the vapor chamber by means of a jet condenser, using water as the condenser medium. The sulfur dioxide gas is dissolved in the water and the less volatile oil vapors are condensed. The oil, vapors and water are passed through a separating chamber, the water being removed from the bottom, the fixed gases from the top, and the oil from the upper layer of liquid above the water.

The oil which is obtained by the method described above is the odorant which is the subject of the present invention. The oil from the separator may be neutralized as with caustic soda, if desired, washed with water, and passed to storage. By the terms "temperature and pressure hydrolysis" and "temperature and pressure distillation", reference is made to products produced by the distillation of sludge (or of sludge tars resulting from hydrolysis of sludge) in which the sludge and tar are subjected to the action of superatmospheric pressure and temperature, thereby distinguishing from processes in which hydrolysis is accomplished by neutralization of sludge with an alkali and other products derived from those processes. When alkali neutralization of sludge is employed, the product does not contain mercaptans which materially enhance the utility of the product for the purposes of this invention. In the attached drawing the figure diagrammatically illustrates one arrangement of elements which may be used for the production of the odorant. It may include, for example, a continuous treater comprising an agitator 1 into which the sulfur-bearing petroleum oil is fed by line 2 and the acid by line 3. The mixture is then discharged into the settling tank 4, the treated petroleum oil being withdrawn through

the line 5 whereas the sludge is discharged by the line 6 into a suitable still or hydrolyzer. An atmospheric pressure type hydrolyzer is illustrated at 7, water and steam being supplied thereto by lines 8 and 9 respectively. A separation into an upper tar or oil layer and a lower aqueous acid layer takes place, the odorant being then passed by line 10 into a fractionating tower 11 from whence the crude odorant is discharged by line 12 into a suitable separating tank 13. The aqueous acid solution may be withdrawn from the bottom of the hydrolyzer 7 as by a valved outlet 14. Water may be withdrawn from the bottom of the settling tank 13 as by the valved outlet 15. The odorant from the settling tank 13 may then pass into a wash tank 16 by line 17. In the wash tank the odorant may be washed with caustic and water supplied through lines 18 and 19 respectively, the spent washing solution being discharged at 20. The washed odorant may then pass into a still 21 by means of a line 22, the odorant being fractionated at 23 and sent to storage by line 24.

The odorant described hereinabove may be employed in any desired manner. For example, it may be introduced into the fuel gas in the form of a spray, although preferably the gas is passed through a tower or other porous bed of material exposing a large surface area over which the odorant is sprayed or held by the absorption of the material with which the tower is packed. In view of the relatively small quantities of odorant necessary to impart a distinctive odor to the gas, the latter method, namely, addition to a column containing rocks, brick or tile, is preferred as more accurate control may be thus maintained over the quantity of odorant added to the gas. One form of odorizer is illustrated in Fig. 2. As there shown, the combustible fuel gas flowing through the line 26 may be discharged into enlarged sections 27 containing series of spaced wicks held in suitable cages and indicated at 28. These wicks 28 may be fed with odorant supplied from a supply tank 29 connected as by conduits 30 with the bottom portions of the wicks. The fuel gas admitted by line 26 passes over and between the wicks, which become thoroughly wetted with the odorant by reason of their capillary action. The odorized gas is then discharged by the line 31.

We claim:

1. A gaseous hydrocarbon fuel having a distinctive and penetrating odor and incapable of producing skin irritation, lachrymation or other undesirable physiological action, said gas fuel being substantially odorless when burned and containing about three gallons per million cubic feet of gas of a volatilized organic oil soluble product having a boiling point range of between 100° F. and 600° F., said product being substantially free of sulfur dioxide and containing organic cyclic sulfides, the effective odorizing constituents of said oil soluble product comprising principally organic cyclic sulfides of the saturated ring heterocyclic type containing three or more carbon atoms and sulfur as a hetero-atom.

2. A gaseous hydrocarbon fuel of the character described, having a distinctive and penetrating odor, said gaseous fuel containing a volatilized organic, sulfur-containing oil resulting from temperature and pressure hydrolysis and distillation of acid sludge formed during sulfuric acid treatment of petroleum oils, said volatilized oil containing organic sulfides, the effective odorizing constituents of the oil comprising prin-

cipally organic sulfides of the saturated ring heterocyclic type containing three or more carbon atoms and sulfur as a hetero-atom.

3. A gaseous hydrocarbon fuel of the character described, having a distinctive and penetrating odor, said gaseous fuel containing a volatilized oil resulting from temperature and pressure hydrolysis and distillation of acid sludge formed during sulfuric acid treatment of petroleum oils, said oil having a boiling point range of between 100° F. and 600° F. and a sulfur content of from 2% to 18%, said volatilized oil containing organic sulfides, the effective odorizing constituents of the oil comprising principally organic sulfides of the saturated ring heterocyclic type containing three or more carbon atoms and sulfur as a hetero-atom.

4. A gaseous hydrocarbon fuel of the character described, having a distinctive and penetrating odor, said gaseous fuel containing a volatilized oil resulting from temperature and pressure hydrolysis and distillation of acid sludge formed during sulfuric acid treatment of petroleum oils, having a distillation end point not above about 420° F. and a sulfur content of from 2% to 18%, said volatilized oil containing organic sulfides, the effective odorizing constituents of the oil comprising principally organic sulfides of the saturated ring heterocyclic type containing three or more carbon atoms and sulfur as a hetero-atom.

5. A gaseous hydrocarbon fuel of the character described, having a distinctive and penetrating odor, said gaseous fuel containing a volatilized oil having a sulfur content of above 2%, containing organic cyclic sulfides, and being substantially free from sulfur dioxide, effective odorizing constituents of the oil comprising principally organic cyclic sulfides of the saturated ring heterocyclic type containing three or more carbon atoms and sulfur as a hetero-atom.

6. A gaseous hydrocarbon fuel having a distinctive and penetrating odor and incapable of producing skin irritation, lachrymation or other undesirable physiological action, said gaseous fuel being substantially odorless when burned, said gaseous fuel containing more than 0.25 part per million of a volatilized organic oil-soluble, temperature and pressure distillation product of acid sludge formed during treatment of petroleum oils with sulfuric acid for the removal of sulfur bodies from such petroleum oils, said distillation product being substantially free from sulfur dioxide and containing over 2% total sulfur, said oil soluble product containing organic sulfides, the effective odorizing constituents of said product comprising principally organic sulfides of the saturated ring heterocyclic type containing three or more carbon atoms and sulfur as a hetero-atom.

7. A gaseous fuel capable of being handled in a normal manner without deleterious effects, comprising; a gaseous combustible hydrocarbon fuel having no marked inherent odor, containing a volatilized oil having a distillation range of between 100° F. and 600° F.; said oil having a total sulfur content of above 2% and containing organic sulfides of the cyclic sulfide type; said oil being a distillation product of acid sludge formed during treatment of sulfur bearing mineral oil with sulfuric acid for the removal of sulfur bodies; said oil having a penetrating signal odor readily discernible in concentrations of about 0.25 part and more per million; said gaseous fuel containing said oil in quantities suffi-

cient to impart a distinctive and penetrating odor thereto but being substantially odorless when burned, the effective odorizing constituents of the oil comprising principally organic cyclic sulfides of the saturated ring heterocyclic type containing three or more carbon atoms and sulfur as a hetero-atom.

8. A gaseous fuel capable of being handled in a normal manner without deleterious effects, comprising: a gaseous combustible hydrocarbon fuel having no marked inherent odor, containing a volatilized oil having a distillation range of between 100° F. and 420° F. and yielding not less than 70% by distillation at 340° F.; said oil having a total sulfur content of above 2% and containing organic sulfides of the cyclic sulfide type; said oil being a distillation product of acid sludge formed during treatment of sulfur bearing mineral oil with sulfuric acid for the removal of sulfur bodies; said oil having a penetrating signal odor readily discernible in concentrations of about 0.25 part and more per million; said gaseous fuel containing said oil in quantities sufficient to impart a distinctive and penetrating odor thereto but being substantially odorless when burned, the effective odorizing constituents of the oil comprising principally organic cyclic sulfides of the saturated ring heterocyclic type containing three or more carbon atoms and sulfur as a hetero-atom.

9. A gaseous fuel capable of being handled in a normal manner without deleterious effects, comprising; a gaseous hydrocarbon fuel containing a volatilized oil having a distillation range of between 100° F. and 420° F.; said oil having a total sulfur content of above 2% and containing organic sulfides of the cyclic sulfide type; said oil being a distillation product of acid sludge formed during treatment of sulfur bearing mineral oil with sulfuric acid for the removal of sulfur bodies; said oil having a penetrating signal odor readily discernible in concentrations of about 0.25 part and more per million; said gaseous fuel containing said oil in quantities sufficient to impart a distinctive and penetrating odor thereto but being substantially odorless when burned, the effective odorizing constituents of the oil comprising principally organic cyclic sulfides of the saturated ring heterocyclic type containing three or more carbon atoms and sulfur as a hetero-atom.

10. A gaseous fuel capable of being handled in a normal manner without deleterious effects, comprising: a gaseous hydrocarbon fuel containing a volatilized oil having a distillation range of between 100° F. and 600° F.; said oil having a total sulfur content of between 2% and 18% and containing organic sulfides of the cyclic sulfide type; said oil being a distillation product of acid sludge formed during treatment of sulfur bearing mineral oil with sulfuric acid for the removal of sulfur bodies; said oil having a penetrating signal odor readily discernible in concentrations of about 0.25 part and more per million; said gaseous fuel containing said oil in quantities sufficient to impart a distinctive and penetrating odor thereto but being substantially odorless when burned, the effective odorizing constituents of the oil comprising principally organic cyclic sulfides of the saturated ring heterocyclic type containing three or more carbon atoms and sulfur as a hetero-atom.

11. A gaseous fuel capable of being handled in a normal manner without deleterious effects, comprising: a gaseous hydrocarbon fuel containing a volatilized oil having a distillation range of

- between 100° F. and 600° F.; said oil having a total sulfur content of between 2% and 18% and containing organic sulfides of the cyclic sulfide type but being substantially free from sulfur dioxide; said oil being a distillation product of acid sludge formed during treatment of sulfur bearing mineral oil with sulfuric acid for the removal of sulfur bodies; said oil having a penetrating signal odor readily discernible in concentrations of about 0.25 part and more per million; said gaseous fuel containing said oil in quantities sufficient to impart a distinctive and penetrating odor thereto but being substantially odorless when burned, the effective odorizing constituents of the oil comprising principally organic cyclic sulfides of the saturated ring heterocyclic type containing three or more carbon atoms and sulfur as a hetero-atom.
12. A gaseous fuel capable of being handled in a normal manner without deleterious effects, comprising: a gaseous hydrocarbon fuel containing a volatilized oil having a distillation range of between 100° F. and 600° F.; said oil having a total sulfur content of above 2% and containing organic sulfides of the cyclic sulfide type but being substantially free from sulfur dioxide; said oil being a distillation product of acid sludge formed during treatment of sulfur bearing mineral oil with sulfuric acid for the removal of sulfur bodies; said oil having a penetrating signal odor readily discernible in concentrations of about 0.25 part and more per million; said gaseous fuel containing said oil in quantities sufficient to impart a distinctive and penetrating odor thereto but being substantially odorless when burned, the effective odorizing constituents of the oil comprising principally organic cyclic sulfides of the saturated ring heterocyclic type containing three or more carbon atoms and sulfur as a hetero-atom.
13. A gaseous fuel capable of being handled in a normal manner without deleterious effects, comprising: a gaseous hydrocarbon fuel containing a volatilized oil having a distillation range of between 100° F. and 420° F. and yielding not less than 70% by distillation at 340° F.; said oil having a total sulfur content of between 2% and 18% and containing organic sulfides of the cyclic sulfide type but being substantially free from sulfur dioxide; said oil being a distillation product of acid sludge formed during treatment of sulfur bearing mineral oil with sulfuric acid for the removal of sulfur bodies; said oil having a penetrating signal odor readily discernible in concentrations of about 0.25 part and more per million; said gaseous fuel containing said oil in quantities sufficient to impart a distinctive and penetrating odor thereto but being substantially odorless when burned, the effective odorizing constituents of the oil comprising principally organic cyclic sulfides of the saturated ring heterocyclic type containing three or more carbon atoms and sulfur as a hetero-atom.
14. A gaseous fuel capable of being handled in a normal manner without deleterious effects, comprising: a gaseous hydrocarbon fuel containing a volatilized oil having a distillation range of between 100° F. and 420° F., said oil having a total sulfur content of between 2% and 18% and containing organic sulfides of the cyclic sulfide type but being substantially free from sulfur dioxide, said oil being a product of hydrolysis and distillation of acid sludge formed during treatment of sulfur bearing mineral oil with sulfuric acid for the removal of sulfur bodies; said oil having a penetrating signal odor readily discernible in concentrations of about 0.25 part and more per million; said gaseous fuel containing said oil in quantities sufficient to impart a distinctive and penetrating odor thereto but being substantially odorless when burned, the effective odorizing constituents of the oil comprising principally organic cyclic sulfides of the saturated ring heterocyclic type containing three or more carbon atoms and sulfur as a hetero-atom.
15. A gaseous fuel capable of being handled in a normal manner without deleterious effects, comprising: a gaseous hydrocarbon fuel containing a volatilized oil having a distillation range of between 100° F. and 600° F., said oil having a total sulfur content of between 2% and 18% and containing organic sulfides of the cyclic sulfide type but being substantially free from sulfur dioxide, said oil being a product of hydrolysis and distillation of acid sludge formed during treatment of sulfur bearing mineral oil with sulfuric acid for the removal of sulfur bodies; said oil having a penetrating signal odor readily discernible in concentrations of about 0.25 part and more per million; said gaseous fuel containing said oil in quantities sufficient to impart a distinctive and penetrating odor thereto but being substantially odorless when burned, the effective odorizing constituents of the oil comprising principally organic cyclic sulfides of the saturated ring heterocyclic type containing three or more carbon atoms and sulfur as a hetero-atom.
16. In a method of producing a heating and illuminating gas having a distinctive signal odor but being substantially odorless when burned, the steps of: vaporizing an oil containing organic cyclic sulfides of the saturated ring heterocyclic type containing three or more carbon atoms and sulfur as a hetero-atom in the gaseous fuel in quantities sufficient to impart a distinctive signal odor to said gas, said odor being distinguishable from the odor of common mercaptans, said oil having a distillation range of between 100° F. and 600° F., a total sulfur content of more than 2%, and being substantially free from sulfur dioxide, the effective odorizing constituents of the oil comprising principally the said organic cyclic sulfides.
